INVENTOR
GAUTIER H. T. LARSEN
BY *Frank Adams*
ATTORNEY

UNITED STATES PATENT OFFICE

GAUTIER HERMAN THAL LARSEN, OF EINDHOVEN, NETHERLANDS, ASSIGNOR TO
RADIO CORPORATION OF AMERICA, A CORPORATION OF DELAWARE

LOUD-SPEAKER

Application filed September 12, 1928, Serial No. 305,365, and in the Netherlands October 8, 1927.

This invention relates to an improved loudspeaker comprising a magnet system and an oscillation member or diaphragm which is operatively connected to the magnet system. 5 The object of the invention is to provide a loudspeaker construction that is so simple that its manufacture can be effected with a minimum outlay so as to permit the manufacturer to deliver the loudspeaker on sale at a 10 very low price.

The loudspeaker, according to my invention, comprises a frame to which the diaphragm is secured, a magnet system for operating the diaphragm, and a strap which is 15 mounted on the frame and on which the magnet system is mounted. The strap is so constructed as to serve as a stand for the loudspeaker. The number of parts of the loudspeaker is thus limited to four pieces, namely 20 by a magnet system, a diaphragm, a frame and a strap.

For attaching the diaphragm to the frame the latter has a circular slit in which a strip of yielding material is clamped by means of 25 a metal ring or hook, the diaphragm being attached to the strip. This enables the diaphragm to move freely at its edge so that it can oscillate as a stiff member.

The strap which is secured to the frame is 30 provided with one or more members which are either pivoted or rigidly connected to the strap and which serve as a stand for the loudspeaker. The frame may be given the shape of a polygon, and one side of the polygon 35 serves, with the member secured to the strap as a support on which the loudspeaker rests. According to one embodiment of my invention the member which is pivoted to the strap is provided with means that enable the attachment of the loudspeaker to a vertical 40 wall.

The component parts of the loudspeaker can be assembled in a very simple manner, only four manipulations being necessary to 45 mount the loudspeaker. Firstly the magnet system is secured to the strap, then the diaphragm which has the strip of yielding material already secured to it is pressed into the slit of the frame, next the strap is secured to the frame so that the driving stud 50

contacts with the diaphragm, finally, the stud is attached to the diaphragm, usually by soldering.

The accompanying drawing illustrates various embodiments of the invention. In 55 the said drawing:

Figure 1 is a side-view of the loudspeaker according to the invention.

Figure 2 is a rear-view of the loudspeaker according to Figure 1. 60

Figure 3 is a side-view of the loudspeaker of Figure 1 in a position in which it is suspended from a vertical wall.

Figure 4 shows the loudspeaker of Figure 1 suspended in a reverse position from a 65 vertical wall.

Figure 5 is a sectional side-view taken on the line V—V of Figure 2.

Figure 6 is a side-view of a different embodiment of the invention. 70

Figure 7 is a rear-view of the construction of Figure 6.

The loudspeaker shown in Figures 1 to 5 consists essentially of an oscillation member or diaphragm 1, a magnet system 2, a frame 3 and a strap 4. The magnet system 2 is not shown in detail as it is irrelevant to the scope of the invention. The magnet system is provided with a driving stud 5 which is connected by soldering or in any suitable 80 manner to the diaphragm 1.

The diaphragm 1 is connected to the frame 3 by means of a yielding annular strip 6 (Figure 5.) The frame has a tapering slit 7 into which the yielding material 6 is clamped by means of a metal ring or hook 8. The clamping member 8 which may be in the form of a split ring, presses the yielding material 6 into the slit 7. The frame 3 has secured to it by means of screws 9 a strap 4 to which the magnet system 2 is secured. This strap is so constructed as to enable its use as a stand for the loudspeaker. For this purpose the strap has pivoted to it a member 11 which, as shown in Figure 1, can be flapped out. The frame is constructed in the shape of a polygon so that one of the sides of this polygon in cooperation with the member 11 can serve as a support for the loudspeaker when the latter is placed on a horizontal plane. The mem- 90 95 100

ber 11 has apertures 12 and 13 which are adapted to receive members of a suitable shape such as hooks in order to suspend the loudspeaker from a vertical wall, as clearly shown in Figures 3 and 4. This construction has the advantage that a loudspeaker can be placed within a room in a very simple manner without affecting the surroundings.

Figures 6 and 7 show a different embodiment of the invention. The difference of this embodiment consists in the shape of the strap 20 which on its lower side is provided with members 21 which are rigidly connected to the strap and serve as a stand for the loudspeaker. Owing to its simple construction this embodiment is also very suitable for the manufacture on a large scale of loudspeakers which are relatively cheap but which are not inferior in quality to the more expensive types.

I claim:

1. A loudspeaker comprising a magnet system, a diaphragm operatively connected with said magnet system, a frame for supporting said diaphragm, a member fastened to said frame for supporting said magnet system and means pivoted to said member for coacting with said frame to form a stand for said loudspeaker.

2. A loudspeaker comprising a magnet system, a diaphragm operatively connected with said magnet system, a frame for supporting said diaphragm, a strap connected across said frame, said magnet system being mounted on said strap, and a member pivoted to said strap for coacting with part of said frame to form a stand for said loudspeaker, said member also being provided with means for enabling the attachment of said loudspeaker to a vertical wall.

3. In combination, a conical diaphragm, means for vibrating said diaphragm, a strip of yielding material fastened around the edge of said diaphragm, a frame having an annular slit and a split ring for clamping said strip of yielding material into said annular slit.

GAUTIER HERMAN THAL LARSEN.
